(57) **CLAIM**

The ornamental design for a housing for electrical connectors, as shown and described.

DESCRIPTION

FIG. 1 is a right side isometric view of a housing for electrical connectors in accordance with the new design;
FIG. 2 is a right side elevation view thereof;
FIG. 3 is a left side elevation view thereof;
FIG. 4 is a top plan view thereof;
FIG. 5 is a bottom plan view thereof;
FIG. 6 is a front elevation view thereof;
FIG. 7 is a rear elevation view thereof; and,
FIG. 8 is a right side isometric view of the housing for electrical connectors of FIG. 1, shown in a typical environment. The portions of the housing for electrical connectors shown in broken lines in FIGS. 5-8 represent unclaimed subject matter and form no part of the claimed design.
